UNITED STATES PATENT OFFICE

VERN L. CHAMBERLIN, OF LAKE ORION, MICHIGAN

DESIGN FOR AN ADVERTISING DEVICE

Application filed June 15, 1931. Serial No. 40,209. Term of patent 7 years.

To all whom it may concern:

Be it known that I, VERN L. CHAMBERLIN, a citizen of the United States, residing at Lake Orion, in the county of Oakland and State of Michigan, have invented a new, original, and ornamental Design for Advertising Devices, of which the following is a specification, reference being had to the accompanying drawings, forming part thereof.

Figure 1 is a front elevation of an advertising device, showing my new design, and

Figure 2 is a side elevation thereof.

The device consists of a rotatably mounted

hub from which extend hollow transparent cylinders closed at their outer ends by solid caps. The cylinders are approximately half filled with fluid, preferably colored, and contain each a ball which floats on the fluid. The fluid is thrown towards the outer ends of the cylinders by centrifugal force as the hub is rotated.

I claim:

The ornamental design for an advertising device, as shown and described.

VERN L. CHAMBERLIN.
